Transport Securing Device Front Wheel Tyre Rocker; 2024; <https://falanparts.com/products/transport-securing-device-front-wheel-tyre-rocker>; 4Pgs. (Year: 2024).*Primary Examiner — Michelle E. Wilson*Assistant Examiner* — Clese Moore, Jr.(74) *Attorney, Agent, or Firm* — Adler Pollock & Sheehan P.C.(57) **CLAIM**

The ornamental design for an device for securing two-wheeled vehicles during transport as shown and described.

DESCRIPTION

FIG. 1 is a perspective front view of the device for securing two-wheeled vehicles during transport according to my new design;

FIG. 2 is a front view thereof;

FIG. 3 is a back view thereof;

FIG. 4 is a side view thereof;

FIG. 5 is an opposite side view thereof;

FIG. 6 is a top view thereof;

FIG. 7 is a bottom view thereof; and,

FIG. 8 is a perspective back view thereof.

The broken lines in the drawings depict environmental subject matter and form no part of the claimed design.
